UNITED STATES PATENT OFFICE.

ALICE J. DEMPSEY, OF WASHINGTON, DISTRICT OF COLUMBIA.

DESIGN FOR A SPOON.

SPECIFICATION forming part of Design No. 21,222, dated December 8, 1891.

Application filed November 12, 1891. Serial No. 411,744. Term of patent 7 years.

To all whom it may concern:

Be it known that I, ALICE J. DEMPSEY, a citizen of the United States, residing at Washington, in the District of Columbia, have invented and produced a new and original Design for Spoons, of which the following is a specification, reference being had to the accompanying drawing, forming a part thereof, which drawing represents a front or obverse view of a spoon embodying my design.

The leading features of my design consist of an open-work handle containing in the center thereof a globe representing the world, and the bowl of the spoon containing a rep-

resentation of the Woman's Building at the 15th World's Fair at Chicago, Illinois.

In the drawing, A and B show the handle. C is the globe representing the world, and D is the bowl, containing the representation of the Woman's Building at Chicago. 20

What I claim is—

The design for a spoon, as shown.

In testimony whereof I affix my signature in presence of two witnesses.

ALICE J. DEMPSEY.

Witnesses:

HENRY C. ROTHROCK,
WM. H. DE LACY.
